UNITED STATES PATENT OFFICE.

FRED A. SCHMITZ, OF CANTON, OHIO, ASSIGNOR TO THE BERGER MANUFACTURING COMPANY, OF CANTON, OHIO, A CORPORATION OF OHIO.

METALLIC SHELVING.

Application filed September 20, 1927. Serial No. 220,879.

This invention relates to an improved type of metallic shelving.

An object of the invention is the provision of metallic shelving which consists of a minimum number of easily fabricated parts; which may be readily assembled without the use of bolts or wedges or tools (other than a screw driver), and which, after assembly, has considerable rigidity and permits of an extremely wide range of adjustment of the shelves.

Another object of the invention is the provision of means to facilitate the positioning of the shelves on supports provided therefor, and means to prevent the accidental displacement of the shelves from such supports.

These and other objects of the invention will become more readily apparent in the course of the following description of the invention, taken in connection with the accompanying drawings, wherein

Fig. 1 is a front elevation, partly in section, of the novel type of shelving;

Fig. 2 is a cross section through the shelving, taken in the line 2—2 of Fig. 1;

Fig. 3 is a perspective view of portions of the shelving;

Fig. 4 is a cross section through the shelving, taken on the line 4—4 of Fig. 2;

30 Figs. 5, 6, 7, and 8 show various modifications of the shelf supports and guards;

Figs. 9, 10, and 11 show modifications of the side flanges of the shelf;

35 Figs. 12, 13, 14, 15, 16, and 17 show modifications of the shelf uprights;

Figs. 18, 19, 20, and 21 show modified forms of the top and bottom plates.

Referring more particularly to the drawings, wherein like parts are designated by 40 like reference characters, the shelving consists of uprights A, bottom plates B, top plates C, and shelves D.

The upright A, in its preferred form, is formed of a rectangular sheet of metal, bent 45 at its approximate center to provide contiguous face members 1 and 2, having flanges 3 and 4 respectively, at their rear edges. Added stiffness is given to the upright by means of one or more stiffener bars 5, vertically disposed between the face members 1 and 2, and at spaced intervals, the face members may be connected as by means of depressed portions 6 which are welded or otherwise secured to each other. The face 55 members 1 and 2 are provided at vertically

spaced intervals with shelf supports 7 and guards 8, which are pressed outwardly from the plane of the face members. The guards 8 which resemble ordinary ventilating louvers are closed at both ends and are provided with an inturned flange 9 which extends the full length of the guard. The shelf supports 7 preferably extend somewhat beyond each end of the corresponding guard, and are formed in such a manner as to leave 60 openings 10 at each end.

Bottom plate B is provided with raised portions 11, having transversely disposed slots 12 therein, and is adapted to be secured to a base structure E, as by means of screws 70 13.

Top plate C is identical in construction with the bottom plate B, and is adapted to be secured to a superstructure F, as by means of screws 14.

75 The shelves D are formed with down-turned side flanges 15, an upturned rear flange or shelf stop 16, and a rolled front flange 17 to reinforce the shelf and give a finished appearance to the front edge thereof. The side flanges 15 are beveled at their rear ends, as indicated at 18, and the rear corners of the top of the shelf are beveled as indicated at 19.

The shelving is assembled in the following 80 manner:

The bottom plates B and the top plates C are secured respectively to the base structure E and superstructure F in such a manner that the slots in the top plate are 85 disposed directly above the slots in the bottom plate. Two or more uprights A are then vertically positioned in any of the several slots 12 in the top and bottom plates, the particular slots selected depending of course 90 on the width of the shelves to be supported between the uprights. The side flanges 15 of the shelves are then entered between the face members 1 and 2 and the shelf supports 7, the beveled portions 18 and 19 of the 95 shelves facilitating such entry. The placing of the shelf on the support is further facilitated by virtue of the fact that the supports extend beyond the ends of the guard. The shelves may then be pushed rearward on the 100 supports as far as desired. The stops 16 serve to prevent articles from falling off the rear of the shelves.

105 The guards 8 effectively prevent upward motion of the shelves after the latter have 110

been properly positioned on the supports, and at the same time serve to prevent the entrance of dust into the supports 7. They also prevent material placed on the shelves 5 from coming into contact with the sharp upper edges of the supports 7, and thereby becoming scratched and damaged.

In Figs. 5, 6, 7, and 8 are shown modified forms of the shelf supports and guards, 10 while in Figs. 9, 10, and 11 are shown modified side flanges for the shelves. The side flanges shown in Figs. 10 and 11 are especially adapted to be used in connection 15 with the shelf supports shown in Figs. 5 and 6.

The uprights may be formed of one piece as described in connection with the preferred form of the invention, or as shown in Figs. 14 and 15, or they may be formed of two 20 parts as shown in Figs. 12, 13, 16, and 17.

The top and bottom plates may be formed as shown in Figs. 18, 19, 20, and 21, without departing from the scope of the invention.

25 The construction of the front flanges of the shelves may be varied to provide the necessary reinforcing strength when long spans or heavy loads are encountered.

Claims—

30 1. Metallic shelving including uprights having vertically spaced, open-ended, shelf supports pressed outwardly beyond the plane of the body of the uprights, and extending from the front to the rear of the uprights, and closed-end guards pressed outwardly beyond the plane of the body of the 35

uprights; said guards being disposed directly above, and alternating with, said supports.

2. Metallic shelving including uprights having vertically spaced shelf supports pressed outwardly beyond the plane of the body of the uprights, and extending from the front to the rear of the uprights, and guards pressed outwardly beyond the plane of the body of the uprights; said guards being disposed directly above, and alternating with, said supports, and terminating short of the ends of the supports. 45

3. Metallic shelving including uprights having vertically spaced, open-ended, shelf supports pressed outwardly beyond the plane of the body of the uprights, and extending from the front to the rear of the uprights, and guards pressed outwardly beyond the plane of the body of the uprights; said guards being disposed directly above, and alternating with, said supports, and terminating short of the ends of the supports. 50

4. Metallic shelving including uprights having vertically spaced, open-ended, shelf supports pressed outwardly beyond the plane of the body of the uprights, and extending from the front to the rear of the uprights, and closed-end guards pressed outwardly beyond the plane of the body of the uprights; said guards being disposed directly above, and alternating with, said supports, and terminating short of the ends of the supports. 55

60 In testimony whereof I affix my signature. 65

FRED A. SCHMITZ.
